UNITED STATES PATENT OFFICE

DAVID LAURENTIUS LIENZÉN, OF STOCKHOLM, SWEDEN, ASSIGNOR TO TELEFONAK-TIEBOLAGET L. M. ERICSSON, OF STOCKHOLM, SWEDEN, A COMPANY OF SWEDEN

SELECTOR CONTACT BANK

Application filed February 25, 1929, Serial No. 342,503, and in Sweden February 28, 1928.

The present invention relates to such selector systems in the automatic telephony in which the incoming and outgoing lines extend through the contact bank perpendicularly to each other and are provided with contact members disposed in the points of intersection which contact members are adapted to be selected and actuated by means of a selecting mechanism disposed in the front of the bank. The object of the invention is to bring about certain improvements in the design of the contact bank for such selectors. More especially, the invention has for its object to make possible the utilization of both sides of the contact banks to establish communication between the incoming and outgoing lines.

The invention will be more closely described with reference to the accompanying drawings which show a selector frame with appertaining selecting mechanisms and contact banks. Figure 1 is a horizontal section through the frame in which section several details are omitted in order to show more clearly the most important parts of the frame together with the devices disposed thereon. Figs. 2a and 2b show horizontal sections of this frame on a larger scale the design of the selecting mechanisms and the contact devices being thus indicated more clearly. Figs. 3a and 3b show portions of the frame seen from below. Figure 4 shows a vertical section of a somewhat modified embodiment of the frame. Figure 5 shows a group of contact arms in front view and Figure 6 shows the fore ends of the contact arms as viewed from above. Figure 7 shows the contact arms in side view together with the appertaining operating device. Figure 8 shows a contact arm as seen from above and Figure 9 the same in side view. Figures 10 and 11 show the shafting of the selecting mechanism, Figure 10 showing the shafts in end view and Figure 11 the same as viewed from above. Figures 12, 13 and 14 are different projections of a shaft bearing.

The frame as shown in Figures 1, 2 and 3 supports a plurality of different selecting mechanisms disposed two and two in horizontal groups which groups are placed above

each other in a vertical arrangement the different selecting mechanisms in each selector pair being disposed on both sides of the centrally disposed contact bank. Each selector is adapted to establish communication between a number of vertically extending wires 1, on the one side, and a number of horizontally extending wires 2, on the other side. In the shown example the wires 1 represent 200 lines each comprising three wires, namely 60 the two speaker wires 3, 4 and the third wire 5 according to Figures 1 and 2. These wires may in this case be assumed to be subscribers lines but they may also be junction lines over which communications are established 65 between different switching sections of an automatic telephone exchange. The wires 1 consist suitably of bare wires extending vertically through several horizontal selector groups in the frame. In the shown example they 70 are disposed in parallelepipedic bundles thus forming parallel wire layers in relation to each other both in such planes which are parallel with the front of the contact bank and in planes perpendicular thereto. Each 75 wire layer disposed perpendicularly to the front of the bank contains six wires appertaining to two different lines. The total number of wires 1 is divided into ten bundles each containing sixty wires corresponding 80 to twenty lines.

The wires 2 may in this case represent such junction lines to which the subscribers' lines 1 are connected. These wires form one vertical single wire layer comprising six bare wires 85 corresponding to two lines each line containing two speaker wires 6, 7 and a third wire 8 in Figure 3. The connection between the wires 1 and 2 is established by means of contact members 9 designed according to Figures 90 8 and 9. Said contact members are secured to the wire 1 in a manner disclosed in the following description and are provided with two contact arms 10, 11 extending in opposite directions. The wires 1 in each wire 95 layer extending perpendicularly to the front of the contact bank are thus connected to six contact members the arms 10 or 11 respectively of which are arranged vertically above each other and extend through the inter- 100

space between the wires 2. Upon being actuated by the selecting mechanism said contact members may establish a simultaneous contact between all wires 1 in the appertaining 5 wire layer, on the one side, and the corresponding wire 2, on the other side, the wires 3, 4, 5 appertaining to one subscribers line being then connected to the wires 6, 7, 8 appertaining to a junction line. Each parallel 10 telepipedic bundle of wires 1 is thus provided with ten groups of contact arms 10 or 11 respectively corresponding to the ten different wire layers. These different groups of contact arms may be selected and actuated 15 by means of a selecting mechanism which will be more closely described in the following. In each setting position of the selecting mechanism two subscribers lines 3, 4, 5 are then simultaneously connected to two junction 20 lines 6, 7, 8. The two lines 6, 7, 8 represent in reality only one junction line as the junction line in known manner is adapted to be connected to either the one or the other of these two wire groups 6, 7, 8 by means of a 25 throwover relay. Only one subscriber's line may thus be connected to said junction line in each setting position of the selector.

The selecting mechanism and the contact bank are supported by a framework which in 30 turn is carried by two vertical beams 12, 13. To these beams two end plates 14, 15 are secured which carry the selectors. Also two vertical channel irons 16, 17 are secured to said end plates and support the framework 35 in which the contact bank is disposed. Said framework consists substantially of a number of pairs of horizontal rods 18, 19 spaced apart a suitable distance and arranged above each other and also a number of thereto secured angle irons 20, 21. The horizontal rods 18, 19 carry the different parallelepipedic bundles of wires 1 by means of a corresponding number of insulating plates 22 provided with holes through which the wires 40 pass. Said plates are by means of screws 23 secured to angular supports 24 which in turn by means of screws 25 are secured to the rods 19. The wires 2 extend in a similar manner through holes in insulating plates 26 which 45 are secured to angle irons 20 and 21 respectively.

The selecting mechanisms are disposed below the appertaining groups of contact arms 50 on both sides of the contact bank. They are 55 mounted on plates 27 and 28 respectively which rest on horizontal angle irons 29 and 30 which are secured to the beams 12, 13 by means of vertical angle irons 31 and 32 respectively, on the one side, and to vertical metal strips 33 and 34 respectively, on the other side, said strips being adapted to tie the angle irons by their outer ends and provided with bent in projections 35 to which the plates 27, 28 may be secured by means of 60 bent up projections 36 on the last mentioned 65

plates and screws 37. The supporting plates 27, 28 engage by their inner edges slots 38 in the end plates 14 according to Fig. 3a. The inner portion of the supporting plates 27, 28 lying between the end plates 14, 15 70 extends inwards against the contact bank and is provided with a vertical edge 39 forming a rear support for the bearing 40 of the selecting mechanism.

Each selecting mechanism consists substantially of two shafts 41, 42 rotatably journaled in the bearings 40 and appertaining driving members which in the shown example consist of two electromagnets 43, 44 which by means of suitable stepping mechanisms comprising toothed wheels 45, 46 disposed on the corresponding shafts may impart a stepwise rotating motion to the shafts. On each supporting plate 27, 28 relays 47 or other apparatus are also mounted which are required for controlling the switching operation of the selector. These relays are mounted on two frames 48, 49 which are swingable on vertical taps 50, 51 and which may be secured in the position shown in Figure 1 by means of screws 52. After loosening these screws said frames with appertaining relays may be swung to the side the selecting mechanism located in the rear being then easily accessible. Each selector is provided with a connecting device the one portion 75 of which is secured to the plate 27 and 28 respectively and the other portion 76 of which is secured to the end plate 14 and 15 respectively, contact being then established by inserting the selector in the frame.

The shafting of the selector may be seen most clearly in Figures 10 and 11. A number of coupling sleeves 53 are thrust on the shaft 42 which sleeves are journaled on rings 54 secured to the shaft 43, on the one side, and in recesses 55 in the bearing block 40, on the other side. The design of said blocks is seen in Figures 12, 13 and 14. They are 105 provided with two bores 56, 57 for the shaft 41, 42 respectively. On the one side, they are provided with a cylindrical bearing surface 58 for a purpose specified in the following. The coupling sleeves 53 are provided with 110 two series of helically disposed studs 59, 60 according to Figure 2. Each series comprises ten such studs distributed over half the circumference of the sleeve. Said studs serve to operate the different groups of contact arms 10, 11 as the same upon turning the sleeve successively actuate the different groups of contact arms disposed vertically above each other. By setting the coupling sleeve 53 in ten different angular positions 115 any of said groups of contact arms may thus be selected and actuated in order to establish communication between the wires 1 and 2. Two series of studs 59, 60 are disposed in order to decrease the angular motion required 120 125 130

for each setting step. After the one series of studs has been used for setting the selector the other series will be used at next setting of the selector, a normal position being disposed between the two series of studs in which no group of contact springs is actuated.

In order to select a line in an arbitrary par-

allelepipedic bundle of wires 1 the coupling sleeves are disposed in such a way that any 10 one of the coupling sleeves may be selected and mechanically coupled to the shaft 42. The selection of the coupling sleeve 53 corresponding to the desired line group is effected by means of the electromagnet 43 and 15 the shaft 41. For this purpose said shaft is provided with two series of coupling studs 59, 60 which are disposed along two helical lines on the shaft in such a manner that each 20 series of studs 59 and 60 respectively extends over half the circumference of the shaft. Said studs are intended to cooperate with the coupling members on the coupling sleeves 53 which coupling members consist of two elastic arms 61, 62 which are secured 25 to the end of the coupling sleeve and at their free ends are provided with a pawl 63 and 64 respectively disposed outside the end of the sleeve which pawl upon being actuated by a stud 59 or 60 respectively may be brought into 30 engagement with a slot 65 or 66 respectively on a coupling ring 67 disposed on the shaft 42. When setting the shaft 41, the coupling sleeves and the coupling then taking up the angular position shown in Figure 5, the 35 studs 59 and 60 respectively will successively actuate the different coupling members 62 so as to bring them into operative position. After the coupling sleeve in this way has been selected and coupled to the shaft 42 40 said shaft is turned by means of the electromagnet 44 in a counter clockwise direction in Figure 10 the coupling member 62 then sliding off from the studs 59 and instead making contact with the cylindrical bearing surface 58 on the bearing block 40 the pawl 64 being maintained in engagement with the ring 67 during the continuous turning motion 45 of the shaft 42. The corresponding coupling sleeve 53 is thus caught and set in a position corresponding to the desired line. The other 50 coupling sleeves 53 remain then in their normal position. Upon interrupting the talking communication the selecting mechanism is returned to normal position by a continued motion of the shaft 41, 42 in the same direction as before until they are returned into 55 their normal positions.

The manner in which the groups of contact springs are actuated is shown in Figure 7 60 where a coupling sleeve for the sake of simplicity is indicated as a toothed wheel 68. Each group of contact springs is adapted to be actuated by means of an elastic arm 69 which is disposed in the frame and by its 65 outer hookshaped end bears against the lower

end of an insulating plate 70, which unites the ends of the contact arms 10 in one and the same group of springs in such a manner that all springs in the same group may be actuated by means of the plate 70. The plates 70 appertaining to the different groups of springs are displaced in relation to each other in the longitudinal direction of the springs as may be seen in Figures 6 and 7. For this reason each other arm 69 is by its outer end provided with an extension 71 in order to reach the corresponding plates 70. The plates 70 are held against the corresponding groups of contact springs by means of stamped out projections 72 in the uppermost and the lowermost contact arm 10, said projections being somewhat elastic so that the plates 70 may be pushed over the ends of the contact arms and retained between the ends of the projections 72.

The contact members are shaped according to Figures 8 and 9. They consist of an elastic metal plate the two outer arms 10, 11 of which are bent over perpendicularly to the middle portion. The latter portion is provided with four stamped out wings 73 which are bent over as shown in Figure 8 and which are elastic so that the contact member may be squeezed and held in position on the appertaining wire 1 solely by the elasticity of the wings 73. In order to keep the contact arms in a suitable distance from the corresponding wire layer the metal plate between said wings 73 is provided with an offset 74 forming a support for the wire 1.

The modification as shown in Figure 4 differs from the embodiment according to Figures 1 to 3 substantially only therein that the supporting plates 27, 28 are disposed below the appertaining contact springs, on the one side, and above the same, on the other side, in order to obtain a complete symmetry in the assembly of the different parts of the frame. Figure 4 shows also the grouping of the selecting mechanisms and the contact bank in larger groups. To each group of 100 subscribers' lines there may belong by way of example sixteen outgoing junction lines provided with sixteen appertaining selecting mechanisms disposed two and two in 110 horizontal groups, each group being disposed above the other. The bottom portion of Figure 4 shows the four upper horizontal groups of such a larger group and the top portion the lower group in another corresponding large group of 200 subscribers' lines disposed above the first mentioned groups in the same frame.

The invention which thus substantially relates to the design of the contact bank is, 125 of course, independent of the character of those selecting mechanisms by means of which the contact arms are selected and actuated. One may thus by way of example instead of the described mechanism make use 130

of relay selectors of a type known per se in which a number of rotatable or displaceable rods are adapted to be actuated by relays in different combinations so that different groups of contact springs may be selected and actuated by energizing these relays in different combinations.

I claim:

1. A selector structure having selector mechanisms arranged on both sides of a contact bank comprising outer bundles of parallel wires arranged on opposite sides of the contact bank, intermediate bundles of parallel wires arranged between said outer bundles of wires and extending parallelly with the sides of the contact bank in a direction perpendicular to the wires of the outer bundles and contact members adapted to be operated by the selector mechanisms and consisting of contact arms secured to the wires of the intermediate bundle and extending to opposite sides of the contact bank.
2. A selector structure as claimed in claim 1, in which the wires of the intermediate bundles are arranged in rows perpendicular to the sides of the contact bank.
3. A selector structure having selector mechanisms arranged on both sides of a contact bank comprising outer bundles of parallel wires arranged on opposite sides of the contact bank, intermediate bundles of parallel wires arranged in rows perpendicular to the sides of the contact bank and disposed between said outer bundles of wires the wires of the intermediate bundles extending parallelly with the sides of the contact bank in a direction perpendicular to the wires of the outer bundles, and contact members adapted to be operated by the selector mechanisms and consisting of contact arms secured to the wires of the intermediate bundles and extending to opposite sides of the contact bank the contact arms of each row of wires being disposed above each other in a plane parallel with the row of wires.

In testimony whereof I affix my signature.

DAVID LAURENTIUS LIENZÉN.
